DESIGN FOR A DAGGER

Norman H. Harstad, Berkeley, Calif.

Application April 21, 1943, Serial No. 110,012

Term of patent 14 years

To all whom it may concern:

Be it known that I, Norman H. Harstad, residing in Berkeley, in the county of Alameda, in the State of California, have invented a new, original, and ornamental Design for a Dagger, of which the following is a specification, reference being had to the accompanying drawing, forming part thereof.

Figure 1 is a plan view of a dagger.

Figure 2 is a side elevational view of a dagger. Figure 3 is a side elevational view of a dagger showing the side opposite to that shown in Figure 2, and

Figure 4 is an end elevational view of a dagger, showing my new design.

I claim:

The ornamental design for a dagger, as shown.

NORMAN H. HARSTAD.
